United States Patent Office.

JAMES S. RAMSAY, OF BALTIMORE, ASSIGNOR TO HIMSELF AND WILLIAM G. HILLMAN, OF LONACONING, MARYLAND.

Letters Patent No. 80,218, dated July 21, 1868.

IMPROVEMENT IN LOCK-LABEL HOLDERS.

The Schedule referred to in these Letters Patent and making part of the same.

TO ALL WHOM IT MAY CONCERN:

Be it known that I, JAMES S. RAMSAY, of the city of Baltimore, and State of Maryland, have invented certain new and useful Improvements in Spring-Lock Baggage-Labels, of which the following is a full, clear, and exact description, reference being had to the accompanying drawings, which make part of this specification, and in which—

Figure 1 represents a view in perspective of my improved spring-lock baggage-label unlocked, and

Figure 2 a vertical longitudinal section of the same locked.

The object of my invention is to provide a simple and convenient device by which travellers can firmly secure their addresses to their baggage, and change the same as often and as rapidly as they may desire, and which will prevent the address from becoming detached, and protect it from injury or obliteration by dust, moisture, or other causes; to which ends my improvement consists in arranging a compartment for the reception of labels, on which addresses may be written or printed, in a suitable case, and locking the side fastening, which holds the labels in position, and staple which attaches the device to the piece of baggage by a single bolt, in such manner that the address cannot be changed or removed or the lock taken off the baggage except by the use of the proper key.

The address being covered by a piece of mica, isinglass, or thin horn, is protected from dust and moisture, and its legibility preserved throughout the journey.

In the accompanying drawings, which show a convenient arrangement of parts for carrying out the objects of my invention, A represents a metallic case, in the form of a thin oval padlock, in the lower portion of which is a label-compartment, E, in which a number of labels, e, upon which addresses can be written or printed, as desired, are placed. An opening is left in the side of the case A, through which the address can be read, the upper label which bears it being covered by a piece of mica, isinglass, thin horn, or other suitable material, by which means it is protected from injury, and its legibility preserved.

A staple B, by which the lock is attached to the piece of baggage which it is desired to mark, is pivoted to the upper part of the case A, the lower portion of its free end being provided with a notch, b, in which the nose d' of a bolt or tumbler, D, within the case, engages and locks it firmly when down. The bolt D is pressed up d' by a spring, d, and released therefrom by the action of a proper key inserted through a key-hole, a, to the notch by a spring, d, and released therefrom by the action of a proper key inserted through a key-hole, a, in the case.

A metallic side-fastening, C, bent to the curve of the periphery of the case, is pivoted thereto in such manner that, when in the position shown by fig. 2, it closes the opening through which the labels are introduced to the compartment E, and prevents them from being changed or removed.

In this position, and when the staple B is pushed down, its lower end bears upon the upper surface of an arm, C', attached to the side fastening C, near the inner end of the said arm, which is provided with a hook or catch, c. The elasticity of the side fastening C presses the arm C' against the end of the staple B, which, being locked by the bolt D, holds the fastening C firmly in position.

When it is desired to change the address, the bolt D is drawn away from the notch b by the key, and the staple B raised, when the side fastening C can be swung downwards upon its pivot, and the requisite address placed uppermost.

It will be seen that the bolt D locks both the staple and side fastening firmly in position, thus preventing the lock from being removed from the piece of baggage or the address being changed, except by the use of the key, when both operations can be readily and quickly performed.

The device is light, and of cheap and simple construction, and its use obviates the annoyance, delay, and expense to which travellers are so frequently exposed by their baggage being improperly forwarded. It affords a ready means of tracing the same, and may, moreover, be used to secure such articles as are not provided with locks.

Having thus fully described my invention, what I claim therein as new, and desire to secure by Letters Patent, is—

1. The combination of the bolt D, staple B, and side fastening C, arranged and operating substantially as described.

2. The compartment E, containing address-labels, which are protected by a sheet of mica, isinglass, thin horn, or similar substance, in combination with a side fastening, which closes the opening through which the same are introduced, and which is locked by a bolt within the case, as set forth.

To the above specification of my invention, I have signed my hand, this 8th day of June, 1868.
